Primary Examiner — Ian Simmons*Assistant Examiner* — Rhea Shields(74) *Attorney, Agent, or Firm* — Garrett V. Davis; Mark S. Bicks; Alfred N. Goodman(57) **CLAIM**

The ornamental design for an electrical receptacle with nightlight, as shown and described.

DESCRIPTION

FIG. 1 is a perspective view of the electrical receptacle with nightlight of the invention;

FIG. 2 is a top view of the electrical receptacle of FIG. 1; FIG. 3 is a right side view of the electrical receptacle of FIG. 1;

FIG. 4 is a left side view of the electrical receptacle of FIG. 1; FIG. 5 is a rear view of the electrical receptacle of FIG. 1; and, FIG. 6 is a front view of the electrical receptacle of FIG. 1. In the drawings, the broken lines depict environmental subject matter only and form no part of the claimed design.
